WEFT SPREADING MACHINE

Arnold Pickup, 193 College St., Magog, Quebec, Canada

Filed Oct. 20, 1960, Ser. No. 63,834

4 Claims. (Cl. 26—54)

This invention relates to a machine intended to stretch or spread the shrunken wefts of woven textile fabrics.

In the textile industry, woven fabrics are subjected to various treatments, after being woven, which cause the weft threads to shrink considerably. In an attempt to overcome this shrinkage, the material is stretched sideways, i.e., the weft threads are spread in a spreading machine known as a stenter frame. In this machine or frame, the edges or selvages of the fabric are held in clips and the material is moved forwardly, while the clips on either side are pulled away from each other, to submit the wefts to a spreading action. At the end of the frame, the clips release their hold on the selvages.

However, spreading by pulling from the selvages only, does not stretch the material uniformly, and, has little effect on the center, because of the great many warp strands that reinforce the material. During this spreading process, the material takes a severe overstretch, and is often fatally damaged, as when there are broken wefts within a short distance from the selvages. This overstretch usually means trouble for the tailors, dress-makers and other garment manufacturers.

An object of the invention is, to provide a machine capable of relieving the shrinkage of textile fabrics by stretching the weft thereof uniformly over the full width, i.e., from the center on to the selvages. Such a machine will greatly reduce the strain to which the wefts are subjected, by dividing the force applied along the full width of the material, instead of from the two longitudinal edges only.

Another object of the invention, is to provide a device that will spread the weft of a fabric in conjunction with the stretching clips of the standard stretching frame, but, by so doing, decreasing considerably the spreading tension to be applied by the clips of the frame.

The invention has also been devised with the object of providing a simple mechanism having a minimum of moving parts so as to render maintenance a matter of secondary importance.

These objects are attained by the provision, between the two parallel series of clips on a stenter weft spreading frame, of at least two sets of rotating disks; each set comprising two disks lying face-to-face with the woven fabric travelling therebetween. The opposing faces of the disks are conical in shape, and by having their axis of rotation make an angle of less than 90° with the horizontal plane of the fabric, they meet along a fixed line in the said plane. Furthermore, this fixed meeting line also makes an angle of less than 90° with the line normal to the line of travel of the fabric. The rotation of the two disks of one set being reverse in relation to the rotation of the two disks of the other set, each weft is subjected to a point-by-point outward stretch.

A better understanding of the invention will be had, by the following description, having reference to the appended drawings wherein:

FIG. 1 is a front elevation view of two sets of two rotating disks as mounted on a spreading frame, one set of disks being shown in cross-section.

FIG. 2 is a front elevation view of another two sets of disks, also partly in section.

FIG. 3 is a view, in plan, of the sets of disks of FIGS. 1 and 2.

FIG. 4 is a side elevation view of the spreader of the invention.

2

The principle of the invention will readily be understood by inspection of FIGS. 1, 2 and 3.

From FIG. 3, it is seen that the woven textile fabric E travels in the direction indicated by arrows M—M. The fabric is held in slightly stretched condition by means of a series of standard clips F, clamping the longitudinal edges or selvages. These clips travel on a stenter G of a known type and release their grip at the end of their forward travel when the spreading operation is terminated.

5 The fabric is held in slightly stretched condition by means of a series of standard clips F, clamping the longitudinal edges or selvages. These clips travel on a stenter G of a known type and release their grip at the end of their forward travel when the spreading operation is terminated.

10 As mentioned above, the material or fabric is forced to move in between pairs of disks, set two-by-two. Each disk has a conical surface made to face the conical surface of the other disk of the set in opposed relationship. In assembled position, these disks are made to contact one another along lines such as AB, A' B', CD and C'D' of FIGURE 3. It will be noted that these lines are offset from the center lines AA' and CC', a predetermined angle.

Although reference is made to contact lines AB, etc., these lines are relatively wide because of the slight pressure applied on the disks and would appear to be properly referred to by the name "radial contact portions."

The angles of inclination of lines AB, A' B' in relation to line AA', which is normal to the direction of travel, are substantially equal so that a weft caught between two points, for instance a point "a" on line AB and a corresponding point "b" on line A' B', will be substantially parallel to line AA'.

Because the meeting line or contact portion, AB, A' B', of the disks is relatively wide, the grip on weft ab will not be instantaneous but will last until each of points "a" and "b" have travelled a short arc of circle. Since the disks move in reverse direction, it will be appreciated that the weft, between points "a" and "b" is subjected to an outward pull which tends to spread or stretch the weft.

In the case of the forward disks of FIG. 3, a similar reasoning may be applied except that in this case, the spreading movement is from point "D" to point "C" and point "D'" to point "C'".

In the above discussion, points A, A', C, C' are, of course, the centers of the disks, whereas points B, B', D, D' are peripheral points.

We now come to a detailed description of the structural features of the invention in a machine using four sets 45 of disks.

The aforesaid sets of disks are mounted on a stenter frame which comprises a series of parallel transverse supports, generally denoted by numeral 1 which may be formed of a U-shaped structural member 3 suitably stiffened by brace 5.

Each spreading assembly itself or a pair of related disks includes a driving disk 7 and a driven disk 9, each generally circular and having a conical surface on one side and a hub 11 on the other side. Each disk, on the hub side, is provided with a central circular recess 12, adapted to receive a supporting pin, 13 for the driving disk 7 and 15 for the driven disk 9.

The tips 17 of pins 13 and 15, which sit in recesses 12, are inclined to the vertical an angle less than 90°, and corresponding to the taper or base angle of the conical faces of disks 7 and 9. Separating these tips 17 from the main body of the pins, 13, 15, are annular abutment flanges 19, which have the surface facing the end of tips 17 normal thereto and, consequently, at an angle to the vertical equal to the taper or base angle of the conical surface of the disks. These latter surfaces face the flat surfaces of the hubs 11, from which they are separated by suitable ball or roller bearings.

Although pins 13 and 15 are held against rotation, they may be made to rotate about their vertical axes, to define the angle of inclination mentioned above in conjunction

with the description of the principle of the invention, i.e., the angle that lines AB, A'B', CD, C'D' make with lines AA' and CC'.

It will be realized, that the diametral line passing by the uppermost point of the inclined annular abutting surface of each flange 19, gives the aforesaid angle of inclination of the disks. Therefore, by rotating this flange 19, the said uppermost point rotates and the angle of inclination varies. A study of FIGS. 2 and 3 will show how this angle is varied by means of a system of levers.

To each upper and lower abutting flange 19 is rigidly fixed a radial arm 23 at the end of which is pivotally connected a lever. The upper and lower levers of the disks P and S will be referred to as levers 27 while the upper and lower levers of disks Q and R will be called levers 29. In the case of upper driven disks 9, arms 23 may be fixed directly onto flanges 19, whereas, on the lower disks 7, they may be connected to a squared end 31 (FIG. 1) of each supporting pin 13. It will be realized, that in order to produce an even spreading of the weft threads, the angle of inclination of lines AB, A'B', CD and C'D' with center lines AA' and CC' must be equal. In the operation of the machine, it would be advantageous to vary this angle simultaneously and through the same variation for the four sets of disks working two by two.

As an example, if it is desired to decrease the angles of contact with lines AA' and CC', levers 27 of disks P and S will have to be moved to the right of FIG. 3 while levers 29 of disks Q and R will have to be moved in the opposite direction, that is, to the left of FIG. 3. Suitable arrows are shown on levers 27 and 29 to indicate the movements. Displacements of the levers in reverse to those just given will, of course, increase the angles of contact. Such movements are obtained by means of the preferred mechanism shown on the right of FIG. 1. The mechanism of FIG. 1 is for the simultaneous actuation and control of disks P and Q. A similar arrangement would be provided for disks R and S.

Upper and lower levers 27 of disks P are connected together through a vertical brace 33, and each one is also joined to a lever 29 of disks Q by the intermediary of a gusset 35. Whereas one end of gusset 35 is rigidly fixed to each arm 27, the other end is a hollow element within which telescopes a lever 29. To prevent rotation of the latter, one or two longitudinal slots 37 are cut on each lever 29, within which fits a pin located inside the hollow element of gusset 35.

Levers 29 are provided with threaded ends 41, received within internally threaded sleeves 43. These sleeves are also threaded on the outside, and rotate within internally threaded members which are part of brackets 39, mounted on structural support 1. The threads on levers 29, are of opposite inclination to those outward threads on bracket members 39, and have a pitch equal to twice the pitch of the said threads of members 39. Consequently, when sleeves 43 move a certain distance in one direction, levers 29 move the same distance but in opposite direction. This is a standard differential screw arrangement.

Vertical brace 33 is fixed against displacement relative to sleeves 43, although the latter are freely rotatable in suitable supporting apertures of the former. Finally, sleeves 43 are set in synchronized rotation by means of sprocket chain and gear arrangement 45 of FIG. 1. A handwheel 47 fixed to one of the gears will provide the necessary rotation when operated.

In FIG. 1, whenever wheel 47 is rotated, sleeves 43 and consequently levers 27, will move in a certain direction a predetermined distance. Because of the specific differential screw arrangement just mentioned, levers 29 will also move the same distance, but in opposite direction. The variation in the angle of inclination of the two sets of disks (P, Q) will be the same for each set.

As aforesaid, a similar arrangement may be provided for the sets of disks R and S.

The driving mechanism for the disks is clearly depicted in FIGS. 1, 2 and 4. All of the power is derived from a common shaft 49, onto which are mounted a series of sprocket wheels 51, connected to driven wheels 53 (FIG. 4) mounted on stub shafts 55 (FIGS. 1 and 2). These shafts 55 are rotatably received in suitable apertures located on two parallel vertical extensions 57 and 59 of cast bodies 21, which bodies further hold driving shaft 49 and are fixed to braces 5 of support 1.

Extensions 57 of cast bodies 21 are sleeve-like in form, and act as seats for supporting pins 13 which, as aforesaid, are rotatable about their axes but are not driven thereabout. Over sleeve extensions 57, and in alignment therewith, are flanged rings 61 also circumscribing supporting pins 13. Each of said rings have an upward surface provided with an annular recess within which rests the abutment flange 19, while a bevelled gear 63 is cut around the peripheral edge thereof. This bevelled gear 63 is driven into rotation by a pinion 65 fixed to one driving stub shaft 55, rotated by means of the sprocket wheel and chain arrangement previously described.

Flanged rings 61 are meant to bring driving disks 7 into rotation. Since the upper surface of rings 61 moves in a horizontal plane while disks 7 rotate in a plane inclined in relation to the former plane, a special driving mechanism has been devised which is best seen in FIG. 4. It consists of one or more sets of two spaced lugs upstanding from the upper surface of flanged rings 61. These lugs cooperatively engage pins 69 projecting downwardly from the under-surface of disks 7. Thus, lugs 67 bring the disks 7 into rotation, by engagement with pins 69 and force them to ride the inclined surface of stationary abutment flange 19. As seen from FIG. 4, pins 69 travel in a vertical reciprocating motion during rotation of the disks 7.

The cooperating conical surfaces of disks 7 and 9 are covered with a rubbery substance, so that, when pressure is made to bear on the upper disks, 9, they will be made to rotate with lower disks 7 by friction existing therebetween. This pressure may be applied by a fluid acting upon the upper face of supporting pins 15, acting as pistons in cylindrical chambers 73 of supporting elements 75 (FIG. 1). This pressure may be fed by a piping system 77 from any suitable source feeding the various upper supporting pins 15 to ensure uniform pressure throughout. By having a resisting spring 79 opposing the action of the fluid pressure within chamber 73, it would be possible to free the disks from one another by simply cutting off the pressure.

To prevent plucking of the material, it is also foreseen that each disk should have a short diameter cavity 90 (FIG. 1) at its center.

What I claim:

1. A weft spreading machine for stretching a travelling woven fabric comprising: at least two pairs of rotating circular disks, said pairs of disks being adjacent and extending across the width of the fabric; the disks of each pair having equiangular conical surfaces disposed in face-to-face relationship and pressed against one another from their apices to the circumferential edges thereof; said woven fabric adapted to move between said pairs of disks in a predetermined direction; upright supports on which the disks of each pair are centrally mounted for rotation; said supports having inclined tips the axes of which extend through the apices of the conical surfaces of said disks so as to allow said surfaces to contact one another along a radial portion lying in the horizontal plane of the woven fabric and means for rotating said supports about their axes so that the radial contacting portions of said pairs of disks made equal angles with said predetermined direction of travel of said fabric.

2. A weft spreading machine for stretching a travelling woven fabric comprising: at least two pairs of rotating circular disks, said pairs of disks being adjacent and extending across the width of the fabric; the disks of each

pair having equiangular conical surfaces disposed in face-to-face relationship and pressed against one another from their apices to the circumferential edges thereof; said woven fabric adapted to move therebetween in a predetermined direction; the disks of each pair being centrally mounted for rotation on supports; the supports including coaxial vertical pins each terminated at one end with an inclined cylindrical tip to allow said conical surfaces of discs of each pair to contact with one another along a radial portion lying in the horizontal plane of the woven fabric; means for rotating said supports of each pairs of discs about the common axis of the pins so that the radial portions of said pairs of disks make equal angles with said predetermined direction of travel of said fabric; the common axis lying in a plane normal to said predetermined direction.

3. A weft spreading machine for stretching a travelling woven fabric comprising: at least two pairs of rotating circular disks, said pairs of disks being adjacent and extending across the width of the fabric; the disks of each pair having equiangular conical surfaces disposed in face-to-face relationship and pressed against one another from their apices to the circumferential edges thereof; said woven fabric adapted to move therebetween in a predetermined direction; the disks of each pair being centrally mounted for rotation on supports having coaxial vertical pins each terminated at one end with an inclined cylindrical tip to allow said conical surfaces of said discs of each pair to contact one another along a radial portion lying in the horizontal plane of the woven fabric; an abutment flange radially extending from each support, on said pin

5 and adjacent said tip, and having a radial surface normal to the tip axis; an abutment surface on each said disk adapted to rest, during rotation, on the flange radial surface; leverage means for rotating said supports of each

5 pair of discs about the common axis of the pins so that the radial portions of said pairs of disks make equal angles with said predetermined direction of travel of said fabric; the common axis lying in a plane normal to said predetermined direction.

10 4. A weft spreading machine as claimed in claim 3, wherein the disks of each pair comprise a lower disk and an upper disk; the pin corresponding to the support of each of the lower disks being received in a cylindrical vertical extension of a supporting body fixed to a frame;

15 a freely rotatable sleeve around said pin over said cylindrical extension; said sleeve having an annular horizontal shoulder over which is located the abutment flange of said support, entrainment means between said shoulder and lower disk; means driving said sleeve into rotation whereby each of said lower disks are brought into rotation through the intermediary of said entrainment means, the upper discs being driven by said lower discs.
